United States Patent Office

Des. 219,822
Patented Feb. 2, 1971

219,822

GAME PROJECTILE

John Rockaitis, 3920 W. 60th Place,
Chicago, Ill. 60629

Filed July 24, 1969, Ser. No. 18,384

Term of patent 14 years

Int. Cl. D21—01

U.S. Cl. D34—5

FIG.1

FIG.2

FIG. 1 is a perspective view of a game projectile showing my new design;

FIG. 2 is a plan view illustrating the game projectile shown in FIG. 1, the reverse side being a mirror image thereof; and

FIG. 3 is a side elevational view of the game projectile of FIG. 2.

I claim:

The ornamental design for a game projectile, as shown and described.
